UNITED STATES PATENT OFFICE.

WILLIAM WALTER FRY, OF PHILADELPHIA, PENNSYLVANIA, ASSIGNOR OF
ONE-HALF TO JOHN P. RICKARDS, OF SAME PLACE.

TAG FOR CARPETS.

SPECIFICATION forming part of Letters Patent No. 373,822, dated November 29, 1887.

Application filed September 22, 1887. Serial No. 250,386. (No model.)

To all whom it may concern:

Be it known that I, WILLIAM WALTER FRY, a citizen of the United States, residing at Philadelphia, in the county of Philadelphia and State of Pennsylvania, have invented certain new and useful Improvements in Tags for Carpets, &c., of which the following is a specification, reference being had therein to the accompanying drawings.

10 The object of my invention is to furnish a tag to be used on rolls of carpet or other similar material which will at a glance show all the data relating to the size of the original roll, the amount sold on particular days, the 15 salesman, &c., and which will be attached to the roll in such a manner that it will be unnecessary to remove it until the roll is entirely disposed of. The tag is also furnished with a strip of elastic webbing, which carries a hook, 20 which keeps the free end of the roll in place without the use of pins or strings.

In the drawings, Figure 1 is a perspective view of a roll of carpet fitted with my improved tag; Fig. 2, a plan of the tag and elastic webbing and hook; Fig. 3, a side view of the same, and Fig. 4 a section of Fig. 3 on line 1 2.

A is a piece of card-board, which is printed in such a manner that all data relating to the 30 piece of goods upon which it is placed may be seen at a glance.

B is a thin piece of metal which backs the card-board and which is furnished with clasps a for holding the card-board securely in place.

35 C is a staple-hook pivoted to the piece of metal B, and which is inserted in the end of a roll of carpet or other material to hold the tag in place.

D is a piece of elastic webbing or its equivalent, secured in any suitable manner to the 40 metal back B. E is a ring carried by this webbing D, and F is a hook carried by the ring E.

The tag is attached to the piece of goods by inserting the staple-hook C into the center of 45 the head of the roll, the barbs b upon this hook preventing it from being withdrawn or from falling from place, while the hook F, carried by the piece of webbing D, secures the free end or edge of the roll, and hence no 50 pins or strings are required to keep this edge in place.

In order that the webbing D and hook F may properly secure the end or edge of the roll, no matter at what part of the roll it may 55 be, the staple-hook C is pivoted to the tag, and the tag may revolve around on this pivot as a center. This pivot, &c., are shown in the section, Fig. 4.

Having thus described my invention, I 60 claim—

1. The combination of the card-board A, metal backing B, clasps a, and staple-hook C, substantially as set forth.

2. The combination of card-board A, metal 65 backing B, clasps a, staple-hook C, pivoted to backing B, elastic webbing D, and hook F, all substantially as and for the purposes set forth.

In testimony whereof I affix my signature in the presence of two witnesses.

WILLIAM WALTER FRY.

Witnesses:

JOHN I. ROGERS,
WM. J. SHETTSLINE.
